UNITED STATES PATENT OFFICE.

CHARLES N. FAY, OF CHICAGO, ILLINOIS, ASSIGNOR TO FAY-SHOLES
COMPANY, OF CHICAGO, ILLINOIS, A CORPORATION.

ESCAPEMENT MECHANISM FOR TYPE-WRITING MACHINES.

No. 804,836.

Specification of Letters Patent.

Patented Nov. 21, 1905.

Application filed January 15, 1903. Serial No. 139,162.

To all whom it may concern:

Be it known that I, CHARLES N. FAY, a citizen of the United States, and a resident of Chicago, county of Cook, and State of Illinois, have invented certain new and useful Improvements in Escapement Mechanism for Type-Writing Machines, of which the following is declared to be a full, clear, and exact description.

The invention relates to an escapement for the usual power-propelled carriage of a type-writing machine, and seeks to provide an effective construction whereby the power of the carriage-driving device will be brought into play to cam or force the shiftable member of the escapement device rapidly back to normal position and whereby the letter-space movement of the carriage in the usual form of escapement will commence as soon as the pressure upon the type-bar finger-keys is released.

The invention consists in the combination and arrangement of parts and in the features of construction set forth in the following description, illustrated in the accompanying drawings, and more particularly pointed out in the appended claims.

In the drawings, Figure 1 is a sectional view of the top plate of the type-writing machine, illustrating the carriage and the improved escapement mechanism. Fig. 2 is a longitudinal section of the escapement mechanism. Fig. 3 is a rear view of the same. Fig. 4 is a sectional view on the line 4-4 of Fig. 2. Fig. 5 is a front face view of the loose escapement-wheel. Fig. 6 is a diagrammatic view of the escapement wheels and dog. Fig. 7 is a similar view, showing a different form of dog.

All parts of the type-writing machine not directly pertaining to the present invention are omitted for the sake of clearness.

The top plate 10 of the machine carries the carriage-rails 11, whereon is movably mounted the carriage 12, which supports the paper-plate 13. The carriage is moved in letter-space direction in the usual manner by a spring-drum 14, which is connected to the carriage by the usual strap 15 and hook 16. A bracket 17 is mounted upon the rear central portion of the top plate 10 and carries at its upper end a bearing or journal-box 18, which is preferably downwardly inclined toward the front of the machine, as shown, and within which is rotatably mounted a short

shaft or journal 19. (See Fig. 2.) To the forward end of the shaft 19 is fixed a pinion 20, which intermeshes with the teeth of a rack 21, mounted upon the carriage. The rack 21 is of usual form and is preferably pivoted, as at 22, to the carriage, so that the rack may be lifted to release the carriage from its escape- ment.

On the rear end of the shaft 19 are mounted two parallel circular escapement racks or wheels 23 and 24. Escapement-wheel 23 is fixed to the shaft or journal 19 by a pin 25 or in any other suitable manner. The circular escapement rack or wheel 24 is loosely mounted upon the shaft 19, but is connected thereto by a coiled spring 26. (See Fig. 2.) The spring 26 is connected at one end to the loose escapement rack or wheel 24 and at the other end to a cap-plate 27. This cap-plate 27, as shown, fits over a reduced portion upon the end of the shaft or journal 19 and incloses the coiled spring 26, and the cap is secured to rotate with a shaft by a nut 28, threaded upon the reduced portion thereof.

Stop devices are provided for limiting the relative throw of the loose escapement rack or wheel 24, which preferably comprises a pin 29, extending through the wheel 23 and projecting into a slot or cut-away portion 30 in the front side of the wheel 24. Slot 30 is of proper width to limit the relative throw of the loose rack 24 to one letter-space.

To adjust the relative position of the escapement-wheels 23 and 24, means are provided for adjusting the position of the stop-pin 29 relatively to the slot 30, and this is conveniently effected by forming the end portion 31 of the pin which engages the slot 30 eccentric to the axis of the pin, as indicated in Fig. 2. Then by rotating the pin 29 within its bearing in the wheel 23 the eccentric stop portion 31 may be conveniently and accurately adjusted.

For convenience in effecting the adjustment the pin 29 is provided with a hexagonal portion 32 or with a slot 33 in its end, which may be engaged by some suitable tool to rotate the pin. A lock-nut 34 is provided on the end of the pin for holding it securely in its adjusted position.

Suitably journaled between uprights 35 upon the rear part of the top plate is a rock-shaft or dog-rocker 36, which is conveniently

connected to the universal bar of the machine by the forwardly-extending arm or arms 37 and links 38.

A dog-holder 39 is secured by screws 40 to 5 an upwardly-projecting central portion 41 of the dog-rocker 36. The dog-holder 39 is U-shaped, (see Figs. 3 and 4,) and the escapement-dog 42, carried thereby, is forked or bifurcated at each end to embrace the ends of the 10 U-shaped dog-holder. The dog 42 is pivoted to one end of the dog-holder, as at 43, and is normally held against a stop 44 (see Fig. 4) upon the opposite end of the dog-holder by a compression-spring 45, said spring being 15 interposed between the dog-holder, 39 and the dog 42, as indicated.

In the form shown the dog is normally in engagement with the loose wheel 24 and is held in such position by a compression-spring 20 46, interposed between the dog-holder 39 and the bracket 17. When the universal bar is depressed by the actuation of any of the type-bar finger-keys of the machine, the dog-rocker is moved forwardly against the tension of spring 46 by the connecting-link 38 and arm 37, so as to bring the dog into engagement with the teeth of the fixed rack or escapement-wheel 23 and hold the carriage in position until the type has struck the paper on the platen, made its impression, and the finger-key released. As soon as the dog is disengaged from the teeth of the loose wheel 24 in such operation said wheel is spaced forward by the spring 26 the distance of one letter-space, 30 and upon the return movement of the dog under the influence of the spring 46 the latter engages the next succeeding tooth of the loose wheel 24, and the carriage is moved forward by its propelling mechanism one letter-space. 35 40 In this operation it will be seen that the letter-space movement of the carriage takes place immediately after the type strikes the platen. The arrangement of parts may be easily modified, so that the dog 42 will normally engage the fixed escapement rack or wheel 23 and be shifted by the operation of the universal bar temporarily into engagement with the loose rack or wheel 24. By 45 the latter arrangement, as will be understood, 50 the operation will be that of the so-called "reversed" escapement—i. e., the letter-space movement of the carriage will take place before the type strikes the platen. Such modification of the parts may be readily effected 55 without departure from the scope of the present invention.

In order to prevent skipping, the dog 42 should, as shown, be wide enough to engage both the escapement racks or wheels simultaneously when passing from one to the other.

In order to securely hold the carriage in normal position, the teeth of the rack or escapement-wheel with which the dog normally engages (in this instance the loose spring-held 60 rack 24) are provided with working faces

which are straight or parallel to the plane of movement of the dog, as clearly shown in Figs. 1, 6, and 7; but in order that the power of the carriage-propelling drum may be brought into play to rapidly cam or force the dog back to normal position the teeth of the other of said escapement racks or wheels (in this instance the fixed wheel 23) are beveled or inclined to the plane of movement of the dog, as indicated in Figs. 1, 4, 6, and 7. By this 70 inclination of the working faces as soon as pressure is relieved upon one of the type-keys the power of the carriage-drum 14, acting upon the ratchet 23, will force the dog 42 rapidly back to normal position and the 75 speed of the escapement will be considerably increased. Moreover, in the form of escapement illustrated in the drawings the letter-space movement may commence as soon as the pressure on the finger-key is released and 80 as soon as the dog commences its return movement—that is to say, the commencement of the letter-space movement is not delayed until the dog is entirely free from the teeth of the escapement-wheel 23, as in prior constructions. The effect of this arrangement is to give the carriage more time to pass from 85 one letter-space position to the next, and in rapid writing the carriage may move its full letter-space distance and come to rest without undue vibration before the next type reaches the paper on the platen, and for this reason the spacing of the writing is much improved and the speed considerably increased. 90

It is obvious that numerous changes may 100 be made in the details of structure without departure from the essentials of the invention as defined by the claims.

Having described my invention, what I claim as new, and desire to secure by Letters 105 Patent, is—

1. In escapement mechanism for type-writing machines, the combination with a power-propelled carriage, of two escapement-racks co-operating with said carriage, one of said racks being spring-held and shiftable relatively to the other, a slot formed in one of said racks, a pin mounted upon the other of said racks projecting at right angles to the plane thereof and arranged to engage said slot, means 110 for adjusting the position of said pin and a shiftable dog arranged to engage said racks. 115

2. In escapement mechanism for type-writing machines, the combination with a power-propelled carriage, of two escapement-racks co-operating with said carriage, one of said racks being spring-held and shiftable relatively to the other, a slot formed in one of said racks, a pin journaled on the other of said racks and having an eccentric portion arranged 120 to engage said slot, the position of which eccentric portion is adjusted by the rotation of said pin and a shiftable dog arranged to engage said racks. 125

3. In escapement mechanism for type-writ- 130

ing machines, the combination with a power-propelled carriage, of a shaft journaled on the machine-frame and operatively connected to said carriage, two escapement-wheels mounted side by side on said shaft, one of said wheels being spring-held and loose on said shaft and the other fixed thereto, a slot in one of said wheels projecting at right angles to the plane thereof, and a pin upon the other of said wheels engaging said slot, means for adjusting the position of said pin a lock-nut for holding said pin in adjusted position and a shiftable dog engaging the teeth of said wheels.

4. In escapement mechanism for type-writing machines, the combination with a power-propelled carriage, of a shaft journaled on the machine-frame and operatively connected to said carriage, two escapement-wheels mounted side by side on said shaft, one of said wheels being spring-held and loose on said shaft and the other fixed thereto, a slot in one of said wheels, a pin journaled upon one of said wheels and having an eccentric portion engaging said slot, the position of which eccentric portion is adjusted by the rotation of said pin, a lock-nut for said pin and a shiftable dog arranged to engage the teeth of said ratchet-wheels.

5. In escapement mechanism for type-writing machines, the combination with a power-propelled carriage, of two parallel escapement-racks coöperating with said carriage, one of said racks being spring-held and shiftable relatively to the other, a slot formed in one of said racks, a pin rotatably mounted on the other of said racks and projecting laterally from the plane of said rack, an eccentric head on said pin arranged to engage said slot, means for rotating said pin to adjust said eccentric portion and a lock-nut for holding said pin in adjusted position.

6. In escapement mechanism for type-writing machines, the combination with a power-propelled carriage, of two parallel escapement-wheels operatively connected to said carriage by a rack and pinion, one of said wheels being spring-held and movable relatively to the other, stop devices for limiting the relative throw of said spring-held wheel, a dog normally engaging one of said wheels and means for shifting said dog to engage the other of said wheels, the teeth of said normally engaged wheel having working faces straight or parallel to the plane of movement of said dog and the teeth of the other of said working faces having beveled or inclined working faces.

7. In escapement mechanism for type-writing machines, the combination with a power-

propelled carriage, of two parallel escapement-wheels operatively connected to said carriage by a rack and pinion, one of said wheels being spring-held and movable relatively to the other, stop devices for limiting the relative throw of said spring-held wheel, a dog normally engaging one of said wheels and means for shifting said dog to engage the other of said wheels, the teeth of said normally engaged wheel having working faces straight or parallel to the plane of movement of said dog and the teeth of the other of said wheels having beveled or inclined working faces and the working faces of said dog having corresponding straight and beveled portions.

8. In escapement mechanism for type-writing machines, the combination with a power-propelled carriage and with a rack mounted thereon, of a shaft journaled on the main frame, a pinion on one end of said shaft engaging said rack, two escapement-wheels mounted upon the opposite end of said shaft, one of said wheels being fixed to said shaft and the other spring-held and loosely mounted thereon, stop devices interposed between said wheels for limiting the relative throw of said spring-held wheel, a shiftable dog normally engaging said spring-held wheel and means for shifting said dog to engage the other of said wheels, the teeth of said spring-held wheel having working faces straight or parallel to the plane of movement of said dog and the teeth of the other of said wheels having beveled or inclined working faces.

9. In escapement mechanism for type-writing machines, the combination with a power-propelled carriage, and with a rack pivoted thereto, of a shaft journaled on the main frame, a pinion on one end of said shaft normally engaging said rack, two escapement-wheels mounted upon the opposite end of said shaft, one of said wheels being fixed and the other spring-held and loosely mounted on said shaft, a slot in one of said wheels, a stop-pin on the other of said wheels and engaging said slot, a vibratory dog normally engaging said spring-held wheel and means for shifting said dog to engage said fixed wheel, the teeth of said loose wheel having working faces straight or parallel to the plane of movement of said dog and the teeth of said fixed wheel having beveled or inclined working faces and the working faces of said dog having corresponding straight and beveled portions.
